UNITED STATES PATENT OFFICE.

CHESTER E. BETCHER, OF MINNEAPOLIS, MINNESOTA.

SMOKE-CONSUMING FURNACE.

Application filed April 26, 1924. Serial No. 709,157.

To all whom it may concern:

Be it known that I, CHESTER E. BETCHER, a citizen of the United States, residing at Minneapolis, in the county of Hennepin and 5 State of Minnesota, have invented certain new and useful Improvements in Smoke-Consuming Furnaces, of which the following is a specification.

My invention relates to smoke consuming furnaces, and an object is to provide means 10 for securing more perfect combustion of fuel than is possible in furnaces which are now in common use. In the customary furnaces which are extensively used only an imperfect combustion of the fuel is obtained 15 and a considerable percentage of the gaseous products passes out into the air in an unconsumed condition. The result is that a large amount of heat is lost and quantities 20 of smoke and soot are discharged into the atmosphere with resultant injurious effects. In carrying out my invention, I provide a firebox construction by means of which the smoke and gases from the fuel are subjected 25 to a high degree of heat before they are given an opportunity to escape through the chimney.

The full objects and advantages of my invention will appear in connection with the 30 foregoing description, and the novel features of my inventive idea will be particularly pointed out in the claims.

In the accompanying drawings which illustrate one form in which my invention 35 may be embodied, Fig. 1 is a view of a furnace in vertical section having my improvement embodied therein. Fig. 2 is a view in vertical section taken at right angles to Fig. 1. Fig. 3 is a view in horizontal section on the line 3—3 of Fig. 2. Fig. 4 is a view in horizontal section on the line 4—4 of Fig. 2. Fig. 5 is a view in horizontal section on the line 5—5 of Fig. 2.

Referring to the construction shown in 45 the drawings, the numeral 10 designates the casing of a furnace or boiler which is shown as a hot water furnace having water passages 12 but it will be understood that the invention is not limited to this type of 50 furnace and may be employed to advantage in other types.

As shown in Fig. 2, the lower portion of 55 the casing 10 encloses a firebox 14 at the rear of which is a combustion chamber 16. The bottom of the firebox consists of a grate hav-

ing fixed grate bars 18 and alternating movable grate bars 20. Two shafts 22 and 24 pass through the grate bars and these shafts where they pass through the movable grate bars are provided with eccentrics 26 which 60 turn in openings in said bars. The shafts 22 and 24 carry crank arms which are connected by a bar 28 whereby the shafts are caused to rotate in unison when a crank handle is applied to one of them so that a 65 four-way motion is imparted to the grate bars 20, this motion consisting of successively rearward, downward, forward, and upward movements which carry the fuel rearwardly when the shafts are operated. The 70 stationary grate bars 18 contain longitudinal air passages 30 having a series of upwardly directed escape openings 32. The passageways 30 at their forward ends are connected with an air supply pipe 34. Between the 75 firebox 14 and the combustion chamber 16 is a firewall 36 which is hollow so that a cooling medium may be introduced. As shown, the interior of the firewall is in communication with the water passages 12 and this firewall 80 extends downwardly from the top of the firebox and is spaced from the bottom thereof. In front of and spaced from the firewall 36 is a vertical grate which in the 85 form shown consists of a plurality of hollow grate bars 38 separated by slots 39 and which extend down from the top of the firebox and are connected at the bottom by a hollow horizontal member 40 spaced above the bottom of the firebox. These grate bars are cooled 90 preferably by being in communication with the water passages 12. At the rear of the grate bars 18 and 20 and forming all or a portion only of the bottom of the combustion chamber 16 is a plate 42 which at its rear edge is pivotally attached to the base member 44. The plate 42 is pivotally attached by being secured to a shaft 46 to which is secured a handle 48 carrying a pin 50 which 95 may be engaged in any one of a number of holes 52. When the pin 50 is pulled out, the plate 42 swings downwardly so as to discharge into the ashpit any ashes and clinkers which have accumulated upon the plate. Furthermore, the plate 42 may be employed 100 as a check damper by adjustably securing it with any desired downward inclination so that more or less cold air from the ashpit will be allowed to pass directly into the 105 combustion chamber without passing 110

through the fire. The plate 42, therefore, serves as a dumping bottom and as a cold air check. A gas or oil jet burner 53 extends into the combustion chamber 16 and this 5 burner may be lit when the fire is low or is being started and it will serve to burn up the smoke which is always present when starting a fire. This burner may also be used when it is desired to crowd the fire. A pipe 10 54 for compressed air is shown extending into the lower portion of the space above the combustion chamber. The compressed air may be turned on and delivered through the pipe 54 when desired for cleaning out the 15 furnace.

The operation and advantages of my invention will be readily understood in connection with the foregoing description. The 20 coal which is placed in the firebox piles up against the lower portion of the vertical grate and the smoke and gases pass between the vertical grate bars and are directed downwardly by the firewall so as to pass into the hottest part of the fire. The movable 25 grate bars when operated move the fuel after it has been fully ignited toward the firewall so that the fire is much hotter at this place than it is in the forward portion of the firebox where fresh fuel is introduced. 30 Ashes and clinkers which accumulate upon the dumping bottom 42 may be readily discharged into the ashpit by tilting this bottom. When the bottom 42 is left in tilted 35 position cold air from the ashpit is allowed to flow into the combustion chamber and check the fire. Compressed air may be

forced through the stationary grate bars when desired to assist in combustion.

I claim:

1. A furnace comprising a firebox, a combustion chamber, a firewall between said firebox and said combustion chamber and spaced above the bottoms thereof, and a grate consisting of vertically disposed, depending grate bars spaced in front of said 45 firewall having its lower end spaced above the bottom of said firebox.

2. A furnace comprising a firebox, a combustion chamber, a firewall between said firebox and said combustion chamber and 50 spaced above the bottoms thereof, a grate consisting of vertically disposed, depending grate bars spaced in front of said firewall having its lower end spaced above the bottom 55 of said firebox, movable grate bars at the bottom of said firebox, and means whereby said grate bars may be operated to feed the fuel towards said firewall.

3. A furnace comprising a firebox, a combustion chamber, a firewall between said 60 firebox and said combustion chamber and spaced above the bottoms thereof, a grate consisting of vertically disposed, depending grate bars spaced on front of said firewall with its lower end spaced above the bottom 65 of said firebox, and a movable horizontal grate for imparting a backward movement to the live coal to bring the partly burned fuel back to and under said vertical grate.

In testimony whereof I hereunto affix my 70 signature.

CHESTER E. BETCHER.
